UNITED STATES PATENT OFFICE.

CHARLES MONTGOMERY POWERS, OF DUBOIS, PENNSYLVANIA, ASSIGNOR
OF ONE-HALF TO M. I. MCCREIGHT, OF SAME PLACE.

COMBINED CANCELING-STAMP AND FILE.

SPECIFICATION forming part of Letters Patent No. 443,405, dated December 23, 1890.

Application filed August 2, 1890. Serial No. 360,794. (Model.)

To all whom it may concern:

Be it known that I, CHARLES MONTGOMERY POWERS, a citizen of the United States, residing at Dubois, in the county of Clearfield 5 and State of Pennsylvania, have invented certain new and useful Improvements in a Combined Canceling-Stamp and File; and I do hereby declare the following to be a full, clear, and exact description of the invention, such 10 as will enable others skilled in the art to which it appertains to make and use the same.

This invention relates to a combined canceling-stamp and file, and has for its object to provide a device which will cancel a check or 15 other negotiable paper or other matter and at the same time place it on file.

The improvement consists of the novel feature and peculiar construction and combination of the parts, which will be hereinafter 20 more fully described and claimed, and which are shown in the annexed drawings, in which—

Figure 1 is a side view, parts being broken away, of a machine embodying my invention. Fig. 2 is a vertical central section of the machine. Fig. 3 is a rear view showing by dotted lines the manner of turning the sleeve to which the head is secured. Fig. 4 is a front view of the head. Fig. 5 is a cross-section on the line X X of Fig. 1.

30 The standard C, projecting up from the base A, is tubular or recessed at its upper end to receive the tubular extension B, which is provided with slots b b, extending lengthwise of the said tubular extension, and which 35 are provided at diametrically-opposite points therein. The sleeve D, mounted on the tubular extension B, is provided at its front side with the vertical slot d and at its rear side with the cam-slot d'. This sleeve D is limited 40 in its downward movement by resting on the shoulder formed at the upper end of the standard C. The lower end of the slot d is provided with the cam-stop e, and the upper end of the cam-slot d' is provided with a corresponding cam-stop e'. The purpose of the 45 cam-stops e and e' is to shift the rod E in the plunger F, so that its end will project into one of the slots d or d'. The spring G, arranged in the standard C and tubular extension B, is 50 adapted to press up on the plunger F and

hold the same at the upper end of its vertical movement, thereby holding the presser-bar H in an operative position. The head I, secured on the sleeve D, has a horizontal slot i in its outer end to receive the check or other paper 55 to be canceled and filed. The stamp J, which may be of any desired pattern, is adapted to work through the upper member k of the head I, and is held at the limit of its upper movement by the spring j. The punch L 60 works vertically in a side extension of the said member k, and is held at the limits of its upper movement by the spring l. The lower member k' of the head I forms a support for the check or other paper which is to be canceled, and is provided in its edge with the notch m, which receives the upper end of the file-holder M when the head is in position to receive the paper to be canceled.

The operation of the invention is as follows: The check or other paper to be canceled or placed on file is inserted in the slot i in the head I, and the plunger is depressed, bringing the pressure-bar H in engagement with the punch L and the stamp J, depressing them. 70 The stamp cancels the check or other paper and the punch coming opposite the end of the file-holder M removes a portion of the said check or paper and files the same on the said file-holder M. When the plunger is depressed, 75 the rod E works in the slots b and d, thereby holding the head I in a fixed position. As the said plunger approaches the limit of its downward movement the rod E engages with the cam-stop e, and at the further movement 80 of the said plunger the cam-stop e shifts the rod E in the plunger, so that its opposite end will engage with the cam-slot d' in the sleeve D. When the plunger is released, the spring 85 G, which has been compressed during the compression of the lever, will expand and lift the plunger. The end of the rod E extending into the cam-slot d' will cause the sleeve D to turn one-quarter way around and bring it back again into its normal position, and as 90 the plunger reaches the limit of its upper movement the said rod E will engage with the cam-stop e', which will shift it so that its end will engage with or project into the slots b and d, as hereinbefore mentioned. When the 100

head is turned to one side, it will be disengaged from the check or paper which has been checked or punched, thereby permitting the said check or paper to slide down on the file-holder M.

5 The stamp, which may be of rubber or metal, may be arranged to print the word "Paid" or other matter desired, and may be constructed to emboss or cut the matter from 10 the body of the paper.

To regulate the speed of the plunger and prevent it from moving up too rapidly, a valve 15 *f* is provided near the lower end of the standard. This valve passes transversely through the standard and is adapted to close the air-opening *f'* in the side of the standard, and its outer end projects beyond the base A. The lower end of the standard B is opened and is closed by the valve N, which is carried on the 20 free end of the spring *c*, the spring and the valve being located in a recess in the said base. When the plunger is depressed rapidly, the air confined in the lower portion of the standard escapes through valve N. As the 25 plunger ascends the valve *d'* closes the lower end of the standard and air enters through opening *f'*. Obviously the rapidity of ascent of the plunger can be regulated by turning valve *f* so as to disclose more or less of the 30 opening *f'*. The spring O, located in the slot *i* of the head I, extends across the lower ends of the stamp and the punch, and is provided to loosen the paper after the operation of the stamp and punch.

35 The file-holder M is a rod on which the check, receipt, or other commercial paper is strung simultaneously with the operation of canceling, thereby obviating a second handling of the paper, as is obvious.

40 Having thus described my invention, what I claim, and desire to secure by Letters Patent, is—

1. A combined canceling and filing stamp composed of a rod M, on which the papers are 45 strung, a stamp arranged close to the file-holding rod, and a punch to act in opposition to the file-holding rod to string the papers thereon, and a plunger and a presser-bar connected with the plunger and adapted to operate 50 the stamp and the punch at one operation, whereby the paper is simultaneously canceled and strung on the said rod, substantially as set forth.

2. The combination, with the standard, the 55 file-holder, and the rotatable head having a canceling and the punching devices, of the plunger and a presser-bar carried by the

plunger and adapted to operate the canceling and the punching devices at the same time, substantially as set forth.

60

3. In a combined stamp and file-holder, the combination, with an extension, as B, having vertical slots in its side diametrically opposite one another, and the sleeve provided with vertical slots in its front side and with a cam-slot in its rear side and having the head which is provided with the canceling and punching devices secured thereto, of the plunger and the rod adapted to work through the plunger and project into either the vertical or cam slots in the said sleeve, substantially as and for the purpose described.

65

4. In a combined stamp and file-holder, the combination of the tubular extension B, having slots *b b*, the sleeve D, having the vertical slot *d* and the cam-slot *d'* and having a cam-stop at the lower end of the slot *d* and a corresponding stop at the upper end of the slot *d'*, the head provided with the canceling and punching devices secured to the said sleeve, the plunger working in the tubular extension, and the rod E, passing through the plunger and adapted to enter the slots *b* and the slots *d* and *d'*, substantially as and for the purpose specified.

70

5. The combination, with the tubular extension B, having slots *b b*, and the sleeve which is adapted to receive a head to which is applied a stamp, and which is provided with a vertical and a cam slot, a cam-stop at the 90 upper end of the slot *d'* and a corresponding cam-stop at the lower end of the slot *d'*, of a plunger, and a rod, as E, working transversely through the plunger, substantially as and for the purpose set forth.

85

6. The combination, with the tubular standard, the file-holder, the rotatable head provided with the canceling and punching devices, and the plunger working in the said standard and adapted to operate the said head and the punching and canceling devices, of the valve N at the lower end of the standard and adapted to open downward, and the regulating-valve *f* for controlling the upward movement of the said plunger and regulating the movement of the said head, substantially as described.

95

In testimony whereof I affix my signature in presence of two witnesses.

CHARLES MONTGOMERY POWERS.
